(No Model.)

J. H. MOUNTFORD.

MACHINE FOR CUTTING POTTERS' PINS.

No. 450,179.

Patented Apr. 14, 1891.

UNITED STATES PATENT OFFICE.

JOHN H. MOUNTFORD, OF EAST LIVERPOOL, OHIO.

MACHINE FOR CUTTING POTTERS' PINS.

SPECIFICATION forming part of Letters Patent No. 450,179, dated April 14, 1891.

Application filed April 4, 1890. Serial No. 346,589. (No model.)

To all whom it may concern:

Be it known that I, JOHN H. MOUNTFORD, a citizen of the United States, and a resident of East Liverpool, county of Columbiana, and 5 State of Ohio, have invented certain new and useful Improvements in Apparatus for Cutting Potters' Pins, of which the following is a specification, the principle of the invention being herein explained and the best mode in 10 which I have contemplated applying that principle so as to distinguish it from other inventions.

My invention relates to machines for making so-called "potters' pins;" and it consists 15 in the improved construction and combination or arrangement of parts hereinafter fully disclosed in the description, drawings, and claims.

The objects of my invention are to provide 20 improved means for cutting potters' pins from wads of partly-dried clay in equal lengths; to provide improved means for admitting of the cutters yielding to obstructions in the wads; to provide improved supports for the wads, and to provide improved means for making 25 the cutter-bearing shaft and cutters interchangeable.

Referring to the drawings, Figure 1 represents a front elevation of my improved machine for cutting potters' pins; Fig. 2, a top 30 plan view of the same; Fig. 3, a longitudinal section on the line 3 4, Fig. 2, and showing the wad-holding arms raised; Fig. 4, a similar view on the same line, showing the wad-holding arms lowered in place; Fig. 5, a perspective view of one of the end pieces of the cutter frame or carriage, and Fig. 6 a longitudinal section of the same.

In said drawings, the letters A A indicate 35 the side sills of the machine-frame, and B B the end sills of said frame, which is suitably supported upon legs or similar supports C. The upper sides of said side sills A have guide-rails α secured upon them, and cleats α' are secured to the inner faces of said sills 40 and serve as supports for the wad-board D, upon which the partly-dried clay-wads are placed to be cut. The upper face of said wad-board D has longitudinal grooves d at distances from each other equal to the lengths 45 to which the pins are to be cut.

Two arms E are pivoted upon the inner faces of the side sills, near the end of the same,

upon pins or bolts e , and have open slots e' in their free ends. Wad-holding arms F are pivoted with pins f in said open slots, and may 55 be swung over the ends of the wad-board and of the wads on the same.

An open cutter frame or carriage G has guide-blocks g upon the under side of its end pieces g' and slides upon the guide-rails α 60 with said guide-blocks. Each of said end pieces g' is formed with a vertical recess g^2 , open at the inner face of the end piece near the lower edge of the same. A bearing-block H, having an open bearing or notch h in its 65 under side, slides in said recess and has a spring I^x , the upper end of which is confined by a strap J, bearing against its upper end. A latch-plate g^3 closes the lower end of said recess, and is pivoted at one end upon a pin 70 or bolt g^4 and has an open slot or notch g^5 at its other end, with which it may slide over a stud g^6 , and thus be held in place.

The cutter-shaft K is journaled with its ends 75 in said upwardly-yielding bearings and has the circular cutters k secured upon it and suitably spaced by washers or similar means. The spaces between the cutters k and between the grooves d in the wad-boards are of the same width, so that said cutters may travel 80 in said grooves.

In practice the wad-holding arms are tilted up, as shown in Fig. 3 of the drawings, the wad-board, with its wads L of partly-dried clay upon it, is placed in position with its ends 85 resting upon the cleats α' , and the wad-holding arms are tilted down over the ends of the clay-wads. The cutter-frame is then drawn from one end of the machine-frame to the other across the wads, which thereby are cut 90 into equal lengths. The wad-board, with its cut wads, is removed, and the operation may be repeated.

When wads of a different length are to be cut, the cutter-shaft may be removed from the 95 carriage in a moment of time by drawing the latch-plate g^3 aside from the bearing and thus admitting of that end of the shaft being tilted downward and the other end withdrawn from its bearing. Another shaft having its cutters 100 at the desired distances apart may be secured in the bearings and the wads cut in the desired lengths, wad-boards having correspondingly-spaced grooves being of course used.

The wad-holding arms can adapt themselves to wads of various thicknesses, as they have pivotal and sliding bearings in the pivoted arms E.

- 5 The shaft may yield upward on account of its spring-bearings, so that a pebble or other hard body in the wads will not injure the edge of the cutter which may strike it, but will simply force the shaft upward and allow 10 the cutter to roll over the obstacle.

The foregoing description and accompanying drawings set forth in detail mechanism embodying my invention. Changes may be made therein, provided the principles of construction respectively recited in the following 15 claims are employed.

I therefore particularly point out and distinctly claim as my invention—

1. In a machine for cutting potters' pins, 20 the combination of a frame formed with longitudinal guides, a carriage sliding in said guides, and a cutter-shaft journaled upwardly yielding in said carriage, substantially as described.
2. In a machine for cutting potters' pins, 25 the combination of a frame formed with longitudinal guides, a carriage sliding in said guides, vertically-sliding spring-cushioned bearings in the ends of said carriage, and a cutter-shaft journaled in said bearings, substantially as described.
3. In a machine for cutting potters' pins, 30 the combination of a frame formed with longitudinal guide-rails, a wad-supporting board 35 transversely supported in said frame and formed with longitudinal grooves in its up-

per face, a carriage sliding upon said guide-rails and formed with upwardly-yielding spring-cushioned bearings, and a shaft journaled in said bearings and provided with cutters spaced to register with and travel in the grooves of said board, substantially as described. 40

4. In a machine for cutting potters' pins, 45 the combination of a frame, a wad-supporting board transversely supported in said frame, two arms pivoted at their ends upon the side sills of said frame and having open slots in their other ends, and wad-holding arms pivoted in said open slots, substantially as de- 50 scribed.

5. In a machine for cutting potters' pins, 55 the combination of a frame provided with guide-rails upon the upper faces of its side sills and with cleats upon the inner faces of the same, a wad-board supported upon said cleats and having longitudinal grooves in its face, arms pivoted upon the inner faces of the side sills and formed with open slots in their ends, wad-holding arms pivoted in said slots, a 60 cutter-frame sliding upon the guide-rails, and a cutter-shaft journaled upwardly yielding in said frame and provided with cutters registering with the grooves in the wad-board, 65 substantially as described.

In testimony that I claim the foregoing to be my invention I have hereunto set my hand this 19th day of March, A. D. 1890.

JOHN H. MOUNTFORD.

Witnesses:

JOHN ROWE,
WM. RANSOM.
